United States Patent Office.

JOSIAH B. BLOOD, OF LYNN, MASSACHUSETTS.

Letters Patent No. 82,280, dated September 22, 1868; antedated September 12, 1868.

IMPROVED CLOTHES-DRIER.

The Schedule referred to in these Letters Patent and making part of the same.

TO ALL WHOM IT MAY CONCERN:

Be it known that I, JOSIAH B. BLOOD, of Lynn, in the county of Essex, and Commonwealth of Massachusetts, have invented a new and improved Mode of Constructing Clothes-Horses or Driers; and I do hereby declare that the following is a full and exact description thereof, reference being had to the accompanying drawings, and to the letters of reference marked thereon, which drawings form part of this specification, and which represent, in—

Figure 1, a perspective view of my improved horse or drier, when opened out nearly to its full extent, and, in

Figure 2, the same when fully closed up and not in use.

The object of this improvement is the production of a folding or jointed frame, or a combination of folding or jointed frames, suitable, when open, for the hanging thereon of clothes or linen after washing, for the purpose of drying or airing the same; also, so to form this frame, that when in position for use, the principal parts may be as nearly as possible in a horizontal position; and further, that the frame, when closed and out of use, shall not be of greater length, nor occupy more space in any direction, than when open.

To secure these objects, I construct my frame, horse, or drier, by connecting, by a convenient number of rods *a a a a*, two opposite sides or frames, formed as follows:

I place the strips A A, B B, across, with a joint at about half their length, permitting them to turn upon each other. This joint is shown at *b*. At about half way between this joint and the lower end of the strip, I attach, on each side, another strip, C C, D D, by a joint of the same description. These last-named strips should not much exceed in length the distance from their joints *c c* to the upper end of the strips to which they are attached.

Near the upper ends of the main strips A A, B B, at *d d*, I attach, by the same kind of joints as before, the two wing-strips E E, F F, having the form shown in the drawings. The point of attachment of these wing-strips, as at *d d*, must be so near the inner ends of the same, that said ends will not touch each other on the opening out of the frame.

I next bring up the side strips, and by similar joints attach them to the wing-strips at *f f*, so that the six strips shall form, when thus connected, a pair of opposite quadrilateral frames, moving easily at the points of junction.

The respective distances, *b c*, *b d*, *c f*, and *d f*, must be so proportioned, relatively to each other, that when the wing-strips E E, F F are, by opening the frame, brought into a horizontal position, the upper inclined surfaces of the main strips A A, B B, seen at *e e e e*, shall find a firm bearing against the side strips C C, D D, to furnish an effective stop to further motion, and the feet of the frame shall at the same time have sufficient extension to secure entire stability.

The length of the wing-strips E E, F F, beyond the joints *f f*, should be nearly the same, both inward and outward, as; if the outward arm be too long, the weight hung upon it may tend to close the frame.

The wing-strips E E, F F, must be placed wholly on the inner side of the other strips to which they are jointed, and the main strip and side strip which are to come in contact to form the stop, must be carefully placed (respectively) in the same plane of motion.

What I claim as my invention, and desire to secure by Letters Patent, is—

The combination of the strips A B, C D, E F, forming the frames, in the manner and for the purpose substantially as above set forth.

JOSIAH B. BLOOD.
